UNITED STATES PATENT OFFICE

150,563

DESIGN FOR A LAMP

Morris Gest, Los Angeles, Calif.

Application August 28, 1946, Serial No. 132,935

Term of patent 3½ years

(CL D48—20)

To all whom it may concern:

Be it known that I, Morris Gest, a citizen of the United States, residing at Los Angeles, in the county of Los Angeles and State of California, have invented a new, original, and ornamental Design for a Lamp, of which the following is a specification, reference being had to the accompanying drawing, forming part thereof.

In the drawing:

Fig. 1 is a side elevation of a lamp, with the lamp shade in its lowered position, showing my new design;

Fig. 2 is a front elevation of the lamp;

Fig. 3 is a side elevation of the lamp with the lamp shade moved upwardly to expose the lamp; and

Fig. 4 is a plan view of the lamp.

I claim:

The ornamental design for a lamp, as shown.
MORRIS GEST.
